[57] CLAIM

The ornamental design for wiping cloth merchandising pail lid, as shown and described.

DESCRIPTION

FIG. 1 is a perspective view of a wiping cloth merchandising pail lid showing my new design;

FIG. 2 is a top plan view thereof;

FIG. 3 is a side elevational view thereof, the opposite side being a mirror image thereof; and,

FIG. 4 is a bottom plan view thereof.

The broken line showing of a container is for illustrative purposes only and forms no part of the claimed design.
